C. S. BROWN.
FEED WHEEL FOR SPOOL MACHINES.
APPLICATION FILED MAR. 9, 1922.

1,421,395.

Patented July 4, 1922.

UNITED STATES PATENT OFFICE.

CHARLES S. BROWN, OF BETHEL, MAINE.

FEED WHEEL FOR SPOOL MACHINES.

1,421,395.

Specification of Letters Patent. Patented July 4, 1922.

Application filed March 9, 1922. Serial No. 542,305.

To all whom it may concern:

Be it known that I, CHARLES S. BROWN, a citizen of the United States, residing at Bethel, in the county of Oxford and State 5 of Maine, have invented certain new and useful Improvements in Feed Wheels for Spool Machines, of which the following is a specification.

My invention relates to a feeding wheel 10 for cylindrical blanks for spool turning lathes.

The spool machine to which my invention is particularly applicable is a machine in common use for turning and finishing spools, 15 such a machine being clearly shown in Patent No. 317,601 dated May 12, 1885.

In this machine and others of its class, cylindrical spool blanks having a central hole are dumped into a hopper from which 20 they are lifted one at a time and discharged into a spout or runway leading to the lathe or spool machine.

The blanks are picked from the hopper by a rotating wheel having arms or spokes 25 which pass through an elongated slot in the bottom of the hopper of approximately the same width as the diameter of the blank.

These arms are provided with pins extending longitudinally forward in the direction 30 of the line of motion of the ends of the arms and as they pass through the elongated slots spoken of, the blanks are picked up one at a time by the pin which enters the central hole in the blank.

35 The blanks are kept constantly stirred and while every spoke does not pick up a blank there are a sufficient number which happen to fall or dispose themselves in such a position as to allow the pin to be thrust 40 through the central hole and be thus raised out of the hopper by the rotation of the wheel.

When the blank thus impaled on the end 45 of the pin reaches the vicinity of the runway or spout it is discharged from the end of the spoke into the spout.

In order to do this, however, mechanism 50 has to be arranged for slipping the blank from the end of the pin so that it may be laterally forced into the spout or runway, and this operation must be quickly done so that the blank after being stripped from the pin may be quickly removed from the path of rotation of the spoke.

55 This operation is the one now commonly

used in such machines and it has certain disadvantages which it is the object of my invention to correct.

In the first place, it is necessary to bore the blanks before they can be treated as I 60 have described and this is done while the blanks are in the shape of a bar, the individual blanks being cut from the bar into approximately the right length for a spool.

Another disadvantage which requires a 65 device of some complication is the necessity for stripping the blank from the pin when both the blank and pin are in motion on the radial spoke.

I overcome these disadvantages in the first 70 place by treating the blank while it is unbored and in the form of a plain cylinder which has simply been cut from a round spool bar.

These cylindrical blanks are charged into 75 the same hopper used in the old machine but they are picked up, one at a time, fitting themselves into a suitable open recess at the extreme end of the radial spoke as the latter passes through the groove in the hopper and 80 are thus raised from the hopper. From the hopper the blank is held in its recess until the discharge point is arrived at.

At this point the blank is simply knocked 85 laterally from the shallow recess which holds it, falling into the feed spout which leads to the lathe.

From the feed spout the blanks pass to the lathe where they may be bored and 90 turned.

I have illustrated my invention by a drawing which shows certain portions of the machine shown in Patent No. 317,601, enough 95 of the drawing of this patent being reproduced to illustrate the use of my invention.

The parts common to my device and the machine illustrated in said patent are lettered as shown in the patent.

In my drawing:

Fig. 1 is a general side view of the wheel 100 as illustrated in Fig. 3 of the patent,

Fig. 2 is a vertical section through the line 2—2 of Fig. 1 at the lower portion of the hopper as shown in Fig. 2 of the patent,

Fig. 3 is a detail section taken on the line 105 1—1 of Fig. 1,

Fig. 4 is a longitudinal vertical section of the spout or runway leading to the lathe, taken on the line 3—3 of Fig. 5,

Fig. 5 is a plan of the spout or runway 110

with adjacent portions of the feed wheel illustrating the manner of discharging the blanks into the spout,

Fig. 6 is a plan of one of my spokes and,
5 Fig. 7 is a side elevation of the same.

Referring to the drawing, B represents the feed wheel and b one of the spokes thereof.

A represents the hopper and a the narrow 10 elongated slot in the bottom thereof and A' is the feed spout leading to the hopper.

At the extreme outer end of my spoke is formed a shallow recess 2 adapted to receive one of the cylindrical blanks D.

15 As here shown, the shallow recess consists of an angular notch formed in the enlarged head 3 of the spoke, the sides of the notch extending at right angles to each other and the axis of the notch or the general direction of the same being in the line of motion of the end of the spoke.

At the rear end of the notch is formed a rest or projection 4 for supporting the end of the blank as it passes upward to the discharge point.

As these spokes pass through the loaded hopper and especially through the narrow portion a, more or less of the blanks will fit themselves into the recess 2 resting against the base 4 and in that position, they are carried to the discharge point above the hopper.

As soon as the spoke lifts the blank from the body of the blanks in the hopper, means 35 are used for holding the spool in its recess until discharged.

For this purpose as herein shown, I provide a curved guide 8 located adjacent to the wheel and curved to follow the path of 40 the blank and the end of the spokes.

As here shown, the guide 8 is formed of two halves secured together by flanges 9 bolted together or otherwise fastened.

The inside surface of the guide is substantially the shape of the blank in cross section so that as the spoke passes upward, the blank is held in position in the recess 2.

Opposite the upper end of the wheel is the feed spout 10 into which the blanks are 50 discharged laterally from the shallow recess 2 as the spokes pass in succession by the end of the spout 10.

Any suitable means may be provided for kicking off the blanks laterally and causing 55 them to roll down the spout. For this purpose, I provide a wire 11 which is secured to the guide 8 being so bent that when the blanks pass the end of the spout 10, it forces it laterally into the spout and out of its 60 recess a.

It is found in practice that my spokes as described pick up a sufficient number of

blanks to keep the spool machine in operation even if each one does not pick up a blank.

My device is also much more simple and practical, requiring less parts than the feeding mechanism used in the old machine.

It is evident that various forms of recess may be used for receiving and carrying the 70 blanks as I have described with its axis practically in the line of motion. Also, other means may be provided for kicking off the blanks from the shallow recess into the feed spout where they are to be discharged. 75

I claim:—

1. In a feeding device for feeding cylindrical blanks for spool and other like machines, the combination of a hopper for the blanks, a wheel rotating adjacent to said hopper and having radial arms passing through said hopper and terminating in radially open recesses closed in the rear of the arms for receiving the blanks, guides for holding the blanks in said recesses as the 80 wheel turns, a feed spout for the spool machine and means for forcing the blanks laterally from said recesses into said feed spout.

2. In a feeding device for feeding cylindrical blanks for spool and other like machines, the combination of a hopper for the blanks, a wheel rotating adjacent to said hopper and having radial arms each terminating in a radially open recess closed in 90 the rear of the arms fitted to receive the blanks when their axes are parallel with the line of motion of said recess, a guide for holding the blanks in said recess as the wheel turns, a feed spout for the spool machine and 95 means for forcing the blanks laterally into said feed spout.

3. In a feeding device for feeding cylindrical blanks for spool and other like machines, the combination of a hopper for the 105 blanks, a wheel rotating adjacent to said hopper and having radial arms passing through said hopper and terminating in radially open recesses closed in the rear of the arms for receiving the blanks, and 110 means for discharging said blanks from said recesses.

4. In a feeding device for feeding cylindrical blanks for spool and other like machines, the combination of a hopper for the 115 blanks, a wheel rotating adjacent to said hopper and having radial arms each terminating in a radially open recess, said recess having adjacent angular sides and a 120 rest or projection at its rear and means for discharging said blanks laterally from said recesses into a feed spout.

CHARLES S. BROWN,
